TRAFFIC MARKER

Anthony Romano, 3974 Jackdaw, San Diego, Calif.

Filed Feb. 25, 1963, Ser. No. 73,707

Term of patent 14 years

(Cl. D72—1)

Fig. 1

Fig. 2

Fig. 3

Fig. 4

Fig. 5

FIGURE 1 is a perspective view of a traffic marker, showing my new design;

FIGURE 2 is a perspective view of the marker with the collapsible portions stowed in the base, the lid being partially open;

FIGURE 3 is a rear elevation view of the erected marker;

FIGURE 4 is a top plan view thereof; and

FIGURE 5 is a side elevation view of the collapsed and closed marker.

I claim:

The ornamental design for a traffic marker, as shown.
